TAKE-UP APPARATUS

Estyle D. Hanson, George E. Henning, and Samuel M. Martin, Baltimore, Md., assignors to Western Electric Company, Incorporated, New York, N. Y., a corporation of New York

Application July 23, 1948, Serial No. 40,226

20 Claims. (Cl. 242—89)

1

This invention relates to takeup apparatus, and more particularly to apparatus for continuously winding strands, such as, for example, insulated conductors.

In strand forming and processing operations, such as in the extrusion of an insulated covering over a conductor and the vulcanization of the covering simultaneously with the extrusion operation, a strand usually is wound upon some type of takeup apparatus, such as a takeup reel, to facilitate storage or further handling of the strand. In the past, when the takeup apparatus is filled with the strand and a new reel or the like must be substituted for the filled takeup apparatus or a switch from one reel to another is made, it usually has been necessary to shut down the processing apparatus during such a substitution or switching. Such interruptions of the process increase the cost of production of the strand, and, in the case of extrusion and vulcanization of insulated coverings upon conductors, the portions of the coverings remaining in the vulcanizing apparatus during the interruptions are overcured so that the corresponding portions of the insulated conductors must be scrapped. Some continuously operable takeup apparatus have been proposed in the past, but this apparatus has been dangerous and generally unsatisfactory.

An object of the invention is to provide new and improved takeup apparatus.

A further object of the invention is to provide new and improved apparatus for continuously winding thereon strands, such as, for example, insulated conductors.

Another object of the invention is to provide new and improved strand takeup apparatus for substantially automatically switching a strand from one takeup reel to another without interrupting the winding process.

A takeup apparatus illustrating certain features of the invention may include a coiling element, a second coiling element, means for rotating the coiling elements, means for guiding a strand along a predetermined path near to and past the first-mentioned coiling element to the second-mentioned coiling element, a snagger revolved with the first-mentioned coiling element and movable from a position at the end of and not extending over the first-mentioned coiling element to a position extending over that coiling element, means for holding the snagger in a position not extending over the first-mentioned reeling element, and means selectively operable for pushing the snagger over the first-mentioned reeling element at a predetermined point in the revolution of the snagger, whereby the snagger catches the portion of the strand guided past the first-mentioned coiling element.

A complete understanding of the invention

2

may be obtained from the following detailed description of an apparatus forming a specific embodiment thereof, when read in conjunction with the appended drawings, in which:

Fig. 1 is a fragmentary front elevation of an apparatus forming one embodiment of the invention;

Fig. 2 is an enlarged, plan view of a portion of the apparatus shown in Fig. 1;

Fig. 3 is an enlarged, fragmentary, front elevation taken along line 3—3 of Fig. 2 with portions thereof, broken away;

Fig. 4 is a fragmentary, vertical section taken along line 4—4 of Fig. 2;

Fig. 5 is an enlarged section taken along line 5—5 of Fig. 3;

Fig. 6 is an enlarged, fragmentary elevation of the apparatus with portions broken away;

Fig. 7 is an enlarged, fragmentary plan view taken along line 7—7 of Fig. 6, and

Fig. 8 is an enlarged, fragmentary view of a portion of the apparatus.

Referring now in detail to the drawings, a conductive core 10 (Fig. 1) is advanced from one of two supply reels 12—12 by a dual capstan 14, and is pulled through an extruder 16, a continuous vulcanizing tube 18 in tandem with the extruder 16, around a guide sheave 19, and through a cooling trough 23 by the dual capstan 14. The extruder 16 forms an insulated covering 24 on the conductive core 10 to form an insulated conductor 26, and the insulated conductor is continuously introduced into the vulcanizing tube 18, which vulcanizes the covering 24 as the conductor 26 is advanced therethrough.

The conductor 26 is advanced from the capstan 14 to a continuous takeup unit 28, and is advanced over a distributor sheave 32 of a distributor 34 either to a takeup reel mechanism 36 operable in one direction or a takeup reel mechanism 38 which is similar to the mechanism 36 but operates in an opposite direction. The distributor sheave 32 is mounted rotatably on an arm 40 (Fig. 3) carried by a distributor head 42 (Fig. 2) supported slidably on a shaft 44 and a rod 46. The shaft 44 and the rod 46 are supported by slides 48—48 mounted slidably on guide rods 50—50 having racks, of which a rack 52 (Fig. 3) is shown, formed thereon.

50 A reversible electric motor 60 (Fig. 2) carried with the slides 48—48 rotates a distributor screw 62 in either of two directions. When the motor is actuated to rotate the distributor screw in one direction, the distributor screw moves the distributor head 42 toward a flange 63 of a reel 34 so that the distributor sheave 32 is moved along the reel 34 to distribute the conductor 26 upon the reel 34 of the takeup reel mechanism 36 which is rotated in a counterclockwise direction, as viewed in Fig. 3. When the distributor

sheave 32 reaches its furthermost near the flange 63 position, an actuating pin 66 carried by the distributor head 42 strikes an arm 68 of a limit switch 70 to reverse the direction of rotation of the motor 68 and the distributor screw 62, whereby the distributor screw moves the head 42 and the sheave 32 toward a flange 69 of the reel 64 to form another layer of the conductor on the takeup reel 64.

When the sheave 32 reaches its furthermost position near the flange 69, an actuating rod 71 strikes an arm 72 of a limit switch 74 to again reverse the direction of rotation of the motor 68 and the distributor screw 62. The actuating rods 66 and 71 are mounted slidably in bosses 76 and 78, respectively, formed on a plate 79 of the distributor head 42. The positions of the rods 66 and 71 may be adjusted by a thumb screw 80 extending through a tapped bore 82 in the plate 79 and tapped bores 85 and 86 formed in arms 69 and 82, respectively, which are rigidly secured to the actuating rods 66 and 71. Thus, the length of throw of the distributor may be adjusted.

A hand wheel 94 is keyed to the shaft 44, which carries two pinions, of which a pinion 96 (Fig. 3) is shown. The pinions 96-96 engage the racks 52-52 of the guide rods 50-50. The hand wheel 94 may be rotated to rotate the shaft 44 and the pinions 96-96 to move the slides 48-49 along the rods 50-50 to the right or to the left, as viewed in Fig. 3, thereby moving the distributor sheave 32 with respect to the takeup reel mechanisms 36 and 38. A pivoted latch 104 may be actuated manually to lock the distributor 34 in any desired position on the guide rods 50-50. Normally, while the covered conductor 26 is wound on the takeup reel mechanism 36, the distributor 34 is in the broken-line position thereof shown in Fig. 3, and the conductor 26 follows a path shown in broken lines to the reel 64. When the reel 64 is almost filled the latch 104 is released and the hand wheel 94 is actuated to move the distributor 34 to the full-line position thereof. This changes the path of the conductor 26 from the distributor sheave 32 to the reel 64 from that shown by the above-mentioned broken-line to the reel 64, to the path thereof shown in full lines. The portion of this path of the conductor 26 between points A and B forms a chord with respect to flanges 100-100 of a reel 110 of the takeup reel mechanism 38, which reel is rotated when driven in a clockwise direction, as viewed in Fig. 3.

An electric motor 116 (Fig. 4) of the takeup reel mechanism 38 then is energized to start the rotation of the reel 110. The motor 116 rotates a centering cone 120 keyed to the reel 110 by a pin 117 and an arm 118 in a clockwise direction, as viewed in Fig. 3, and a freely rotatable centering cone 122 (Fig. 4) connected to the reel 110 by a pin 121 and a guard 124 is rotated by the reel. The centering cone 122 is rotated by the reel 110 and rotates the guard 124 therewith. The guard 124 carries an L-shaped snagger 128 pivotally thereon and the snagger has a snagging notch 130 formed therein. The snagger 128 is designed to slide through a slot 132 formed in the guard 124. An arm 126 of the snagger 128 carries a follower roller 133, and normally is held by a spring 134 in a retracted position in which the snagging portion of the snagger 128 does not extend beyond the near flange of the reel 110. A presser cam 135 is carried by an arm 136 pivotally mounted on a bearing 137, and is operable by a lever 138

to a position engaging the roller 133 to move the snagger 128 further upwardly, as viewed in Fig. 5, to a position extending beyond the inner flange of the reel 110 shortly after the 5 snagger passes the point A (Fig. 3). However, as the snagger passes point A the cam does not push the snagger beyond the near reel flange 100 and against the spring 134 but acts to hold the snagger in its retracted position so that the 10 snagger clears the conductor 26 whenever the conductor is near that flange of the reel as the snagger approaches the portion of the conductor 26 at the point A.

When the distributor sheave 32 advances the 15 conductor 26, which subtends a portion of the flanges of the reel 110, to a position in which the conductor is near the right hand flange of the reel, as viewed in Fig. 4, and the lever 138 has been actuated to push the snagger against the 20 spring 134, the snagger clears the portion of the conductor at point A (Fig. 3), is moved over the conductor between the points A and B, catches the portion of the conductor at point B in the notch 130 (Fig. 7) and pulls the conductor downwardly, as viewed in Fig. 3. The takeup reel 94 continues to be rotated and to wind the conductor 26 thereon, and the portion of the conductor between the snagger and the reel 64 is moved downwardly. The inrunning reel 64 and 25 the snagger 128 move the portion of the conductor therebetween downwardly hard against a shear blade 140 to sever the conductor.

The snagger 128 continues to rotate with the 30 reel 110 and the distributor 34 distributes the conductor 26 on the reel 110 as the snagger is rotated beyond the point B (Fig. 3) to somewhere near point C where the snagger moves out of engagement with the cam, and the spring 134 moves the snagger back to a position in which 35 it does not extend over the flange of the reel 110. The snagger continues to hold the conductor so that the conductor is wound on the reel 110. The lever 138 then is released and the snagger is moved to its retracted position by the 40 spring 134 to clear the portion of the conductor 26 being advanced to the reel 110. Thus, after the winding has been started on the reel 110 as described hereinabove, there is no danger of 45 resnagging the conductor 26.

After the reel 110 has been filled the distributor 50 34 is moved to its broken-line position and the above-described operation in connection with starting and winding of the conductor 26 on the reel 110 is repeated to shear the conductor and start the conductor on the reel 64 by means of 55 a snagger and its associated elements which form a portion of the takeup reel mechanism 36, which is identical with the takeup mechanism 38 except that the mechanism 36 is a left hand mechanism while the mechanism 38 is a right hand 60 mechanism.

The motor 116 (Fig. 4) is mounted on a slide 65 170 mounted on a guideway 172, and a bearing 174 supporting the centering cone 120 also is carried by the slide 170. After the reel 110 has been filled and the conductor 26 is severed therefrom, the motor 116 is deenergized and a linkage 176 is moved so as to actuate a valve 178 to supply air under pressure to the right hand end 70 of a cylinder 180, as viewed in Fig. 4, and to pivot a latch 182 secured rigidly to a shaft 184 out of a slot 186 formed in the slide 170 so that the slide may be slid to the left by a piston 194 fastened to the slide to free the reel 110 for removal. After an empty reel to be substituted 75 for the reel 110 has been positioned between

the centering cones 120 and 122, the linkage 176 is moved to actuate the valve 178 to supply air under pressure to the left end of the cylinder 180 and to permit the latch 182 to move into the slot 183 whenever the slot 183 is moved thereover. The piston then moves the slide 178 to mount the empty reel on the centering cones 120 and 122, and the latch moves into the slot 183 to latch the slide in an operative position.

Operation

The insulated conductor 26 is advanced over the sheave 32 of the distributor mechanism 34, which is in its broken-line position, as viewed in Fig. 3, to the reel 64 of the takeup reel mechanism 36, the motors 60 and 65 are started, the reel 64 is rotated, and the distributor 34 distributes the conductor 26 in layers extending from flange to flange of the reel 64. When the reel 64 is almost filled, an operator of the apparatus releases the latch 184 and moves the distributor mechanism 34 to the left to its full-line position. The operator then starts the motor 116 (Fig. 2) to rotate the reel 110 in an inrunning direction with respect to the direction of rotation of the reel 64, and the distributor 34 continues to distribute the conductor evenly upon the reel 64.

When the reel 64 is filled, the operator actuates the lever 138 (Fig. 4) to swing the cam 139 to the left, as viewed in Fig. 4. The snagger 128 then is moved from a position at the edge of the right hand flange of the reel 110 to the position of the snagger 128 shown in Fig. 5 after the snagger has passed point A (Fig. 3) and has not yet come to point B. After the snagger is rotated past point C the follower roller 133 moves it back to a position in which it does not extend beyond the inner flange 109 of the reel 110. When the distributor sheave 32 moves the conductor 26 to the right hand flange of the reel 110, as viewed in Fig. 4, the snagger 128 catches the conductor 26 and moves the portion of the conductor between the snagger and the reel 64 against the shear blade 140, which severs the conductor.

The lever 138 then is released so that the spring 134 moves the snagger 128 to its retracted position. The snagger continues to hold the newly formed end of the conductor 26 and carries it around the drum of the reel 110, and the distributor 34 distributes the conductor on that reel.

The operator then stops the takeup reel mechanism 36, removes the filled reel 64 therefrom, and substitutes an empty reel identical with the reel 64 for the reel 64. When the reel 110 is filled with the conductor 26, the switchover to the empty reel of the takeup reel mechanism 36 is effected by a snagger and its associated elements of the reel mechanism 36 which are identical with but of opposite hand from the snagger 128 and its associated elements of the takeup mechanism 36, after moving the distributor 34 to its broken-line position, as shown in Fig. 3, so that a portion of the conductor 26 between the sheave 32 and the takeup reel 110 is in a plane chordally intersecting the flanges of the reel of the takeup mechanism 36 to permit the conductor to be snagged.

The above-described takeup mechanism serves to continuously take up the conductor 26 without interruption in or slowing of operation so that the operation of the extruder 16 and the vulcanization is not even slowed down. The transfer from one takeup mechanism to the other is almost completely automatic inasmuch as the only manual effort necessary to make a transfer from

one takeup reel mechanism to the other is to move the distributor mechanism 34 to the proper position, to start the idle takeup reel mechanism, to actuate the cam of the idle takeup mechanism and to release the cam after the transfer has been made. There is no danger to an operator of the apparatus since the snaggers are covered and accidental contact therewith is blocked.

Certain features of the above-described apparatus are disclosed and claimed in copending application Serial No. 40,290, filed July 23, 1948, by D. C. Robson.

What is claimed is:

1. A takeup apparatus, which comprises a coiling element, a second coiling element, means for rotating the coiling elements, means for guiding a strand along a predetermined path near to and past the first-mentioned coiling element to the second-mentioned coiling element, a snagger revolved continuously with the first-mentioned coiling element and movable from a position at one end of and not extending over the first-mentioned coiling element to a position extending over that coiling element, means for holding the snagger in a position not extending over the first-mentioned coiling element, and selectively operable means for pushing the snagger over the first-mentioned coiling element at a predetermined point in the revolution of the snagger, whereby the snagger catches the portion of the strand guided past the first-mentioned coiling element.

2. A takeup apparatus, which comprises a coiling element, a second coiling element, means for rotating the coiling elements, means for guiding a strand along a predetermined path near to and past the first-mentioned coiling element to the second-mentioned coiling element, a snagger revolved continuously with the first-mentioned coiling element and movable from a position at one end of and not extending over the first-mentioned coiling element to a position extending over that coiling element, means for urging the snagger to a position not extending over the first-mentioned coiling element, means for pushing the snagger against the snagger-urging means to the position in which it extends over the first-mentioned coiling element at a predetermined point in the revolution of the snagger, whereby the snagger catches the portion of the strand guided past the first-mentioned coiling element, and a cutter positioned in the path in which the portion of the strand between the snagger and the second-mentioned coiling element is moved by the snagger for severing the strand.

3. A takeup apparatus, which comprises a coiling element, a second coiling element, means for rotating the coiling elements, means for guiding a strand along a predetermined path near to and past the first-mentioned coiling element to the second-mentioned coiling element, a snagger revolved continuously with the first-mentioned coiling element and movable from a position at one end of and not extending over the first-mentioned coiling element to a position extending over that coiling element, means normally operable for urging the snagger to a position not extending over the first-mentioned coiling element, and means selectively operable for pushing the snagger against the action of the snagger-urging means to the position in which it extends over the first-mentioned coiling element at a predetermined point in the revolution of the snagger, whereby the snagger catches the portion of the strand guided past the first-mentioned coiling element.

4. A takeup apparatus, which comprises a pair of reels, means for rotating the reels, a snagger provided with a strand catching and gripping portion revolved continuously with one of the reels, a cam selectively operable for moving the snagger over the last-mentioned reel, means selectively operable for guiding a strand past one of the reels to the other reel into the path of the snagger, and a cutter so positioned with respect to the snagger that the portion of the strand between the snagger and the reel to which the strand is guided is moved into engagement with the cutter and severed.

5. A takeup apparatus, which comprises a pair of transversely aligned reels, means for rotating the reels, means for guiding a strand past one of the reels to the other reel, a snagger provided with a strand-catching-and-gripping portion revolved continuously with the reel past which a strand is guided, a cutter positioned between the snagger and the other reel, and a selectively operable cam for projecting the strand-catching-and-gripping portion beyond the flange of the reel past which the strand is guided to catch and grip the strand, whereby the portion of the strand between the snagger and the reel to which the strand is guided is moved into engagement with the cutter and severed.

6. A takeup apparatus, which comprises a pair of transversely aligned reels, means for rotating the reels in inrunning directions, means for guiding a strand past one of the reels to the other reel, a snagger provided with a strand catching and gripping portion revolved continuously with the reel past which a strand is guided, a cutter positioned between the snagger and the other reel, and selectively operable means for projecting the strand-catching-and-gripping portion beyond the flange of the reel past which the strand is guided to catch and grip the strand, whereby the portion of the strand between the snagger and the reel to which the strand is guided is moved into engagement with the cutter and severed.

7. A takeup apparatus, which comprises a rotatable takeup unit, a second rotatable takeup unit, means for rotating the units on parallel axes and for mounting the units in transversely aligned positions, means for guiding a strand past the first-mentioned takeup unit to the second-mentioned takeup unit, a snagger carried continuously with the first-mentioned takeup unit and movable from a position with respect to that unit in which the strand is not engaged thereby to a position in which the strand is snagged thereby, means for urging the snagger toward the first-mentioned position thereof, and an actuator selectively operable for moving the snagger against the snagger-urging means to the position of the snagger in which the snagger snags the strand.

8. A takeup apparatus, which comprises a winding element, means for rotating the winding element, a snagger carried continuously by one end of the winding element and movable from a retracted position in which the snagger does not project over the winding element to a snagging position in which the snagger does project over the winding element, means for urging the snagger toward the retracted position thereof in which the snagger does project over the winding element, and means selectively operable for moving the snagger for a predetermined portion of the revolution of the snagger to the snagging position thereof in which it projects over the wind-

ing element so that the snagger clears one portion of a strand guided chordally with respect to the path of the snagger and catches a second portion of the strand.

5 9. A takeup apparatus, which comprises a rotatable winding element, means for rotating the winding element, an L-shaped snagger carried continuously and pivotally by one end of the winding element and having a strand-snagging portion movable from a retracted position in which that portion does not project over the winding element to a snagging position in which it does project over the winding element, means for guiding a strand in a plane chordal with respect to the path of the strand-snagging portion of the snagger, means for urging the strand-snagging portion of the snagger to the retracted position thereof, and a cam selectively operable for projecting the strand-snagging portion of the snagger over the winding element as the strand-snagging portion approaches a predetermined portion of the strand.

10 10. A takeup apparatus, which comprises a reel, means engaging one end of the reel for rotating the reel, reel-mounting means for engaging the other end of the reel and rotatable thereby, a snagger extending radially beyond the reel, carried continuously with the reel by the reel-mounting means and movable from a retracted position in which the snagger does not project over the more adjacent head of the reel to a snagging position in which the snagger does project over the more adjacent head of the reel, means for urging the snagger to its retracted position, and means selectively operable for moving the snagger to the snagging position thereof for a predetermined portion of the revolution of the snagger.

11. A takeup apparatus, which comprises a 40 rotatable reeling element, a second rotatable reel element, means mounting the reeling elements in transversely aligned positions for rotating the reeling elements in inrunning directions, an arm carried continuously with and mounted pivotally at the end of the first-mentioned reeling element, a snagger carried by the arm and extending substantially parallel to axis of rotation of the first-mentioned reeling element and radially outside that reeling element so that the snagger is projected over that reeling element when the arm is pivoted toward that reeling element, said snagger being revolved in a predetermined circular path beyond the radial limits of the first-mentioned reeling element, a distributor adjustable transversely to the axes of rotation of the reeling element for distributing a strand upon the second-mentioned reeling element and for guiding the strand to the second-mentioned reeling element in a plane chordally intersecting the path 50 of the snagger, means for urging the snagger to a retracted position beyond the near end of the first-mentioned reeling element as the snagger is moved past the portion of the strand entering the portion of the plane chordally intersecting the path of the snagger so that the snagger clears that portion of the strand, and means selectively operable for moving the snagger to a snagging position extending over the near end of the first-mentioned reeling element after the snagger has 60 been moved past the portion of the strand entering said portion of said plane and before the snagger has been moved to the portion of the strand leaving said portion of said plane and for holding the snagger in its snagging position as 65 the snagger is moved to and past the point at 70 75

which the strand leaves said portion of the plane so that the snagger catches and grips the strand as the strand is moved past the near end of the first-mentioned reeling element.

12. A takeup apparatus, which comprises a rotatable reeling element, a second rotatable reeling element, means mounting the reeling elements in transversely aligned positions for rotating the reeling elements in inrunning directions, a snagger rotatable continuously with the first-mentioned reeling element and having a snagging portion extending substantially parallel to axis of rotation of the first-mentioned reeling element and radially outside that reeling element, means mounting the snagger for movement relative to the first-mentioned reeling element such that the snagging portion is projected over that reeling element when the snagger is moved toward that reeling element, the snagging portion of the snagger being revolved in a predetermined substantially circular path beyond the radial limits of the first-mentioned reeling element, a distributor for distributing a strand upon the second-mentioned reeling element and for guiding the strand to the second-mentioned reeling element in a plane chordally cutting the path of the snagger, means for urging the snagger to a retracted position in which the snagging portion thereof is beyond the near end of the first-mentioned reeling element as the snagging portion is moved past the portion of the strand entering the portion of the plane chordally intersecting the path of the snagging portion so that the snagging portion clears that portion of the strand, a manually operable cam for moving the snagger to a snagging position in which the snagging portion extends over the near end of the first-mentioned reeling element after the snagging portion has been moved past the portion of the strand entering said portion of said plane and before the snagging portion has been moved to the portion of the strand leaving said portion of said plane and for holding the snagging portion in the position extending over the near end of the first-mentioned reeling element as the snagging portion is moved to and past the point at which the strand leaves said portion of the plane so that the snagging portion catches and grips the strand as the strand is moved past the near end of the first-mentioned reeling element, and a cutter positioned outside the circular path of the snagging portion and in the path in which the portion of the strand between the snagger and the second-mentioned reeling element is moved by the snagger for severing the strand.

13. A takeup apparatus, which comprises a rotatable reeling element, a second rotatable reeling element, means mounting the reeling elements in transversely aligned positions for rotating the reeling elements in inrunning directions, a snagger carried continuously with the first-mentioned reeling element at an end thereof and extending substantially parallel to axis of rotation of the first-mentioned reeling element and radially outside that reeling element, the snagger being projectable over the first-mentioned reeling element and being revolved in a predetermined circular path beyond the radial limits of the first-mentioned reeling element, a distributor movable transversely to the axis of rotation of the reeling element for distributing a strand upon the second-mentioned reeling element and for guiding the strand to the second-mentioned reeling element in a plane chordally cutting the path of the snagger, means for pre-

venting snagging action of the snagger as the snagger is moved past the portion of the strand entering the portion of the plane chordally intersecting the path of the snagger, and cam means selectively operable for actuating the snagger after it has been moved past the portion of the strand entering said portion of said plane and before the snagger has been moved to the portion of the strand leaving said portion of said plane and for holding the snagger in the position extending over the near end of the first-mentioned reeling element as the snagger is moved to and past the point at which the strand leaves said portion of the plane so that the snagger catches and grips the strand as the strand is moved past the near end of the first-mentioned reeling element.

14. A takeup apparatus, which comprises a coiling element, a second coiling element, means for rotating the coiling elements, means for guiding a strand along a predetermined path near to and past the first-mentioned coiling element to the second-mentioned coiling element, a snagger revolved continuously with the first-mentioned coiling element and movable from a position at the end of and not extending over the first-mentioned coiling element to a position extending over that coiling element, means for holding the snagger in a position not extending over the first-mentioned reeling element, selectively operable means for pushing the snagger over the first-mentioned coiling element at a predetermined point in the revolution of the snagger, whereby the snagger catches the portion of the strand guided past the first-mentioned coiling element, and a cutter positioned in the path in which the portion of the strand between the snagger and the second-mentioned coiling element is moved by the snagger for severing the strand.

15. A takeup apparatus, which comprises a coiling element, a second coiling element, means for rotating the coiling elements, means for guiding a strand along a predetermined path near to and past the first-mentioned coiling element to the second-mentioned coiling element, a snagger revolved continuously with the first-mentioned coiling element and movable from a position at the end of and not extending over the first-mentioned coiling element to a position extending over that coiling element, means normally operable for urging the snagger to a position not extending over the first-mentioned reeling element, means selectively operable for pushing the snagger against the action of the snagger-urging means to the position in which it extends over the first-mentioned reeling element at a predetermined point in the revolution of the snagger, whereby the snagger catches the portion of the strand guided past the first-mentioned coiling element, and a cutter positioned in the path in which the portion of the strand between the snagger and the second-mentioned coiling element is moved by the snagger for severing the strand.

16. A takeup apparatus, which comprises a rotatable takeup unit, a second rotatable takeup unit, means for rotating the units on parallel axes and for mounting the units in transversely aligned positions, means for guiding a strand past the first-mentioned takeup unit to the second-mentioned takeup unit, a snagger carried continuously with the first-mentioned takeup unit and movable from a position with respect to that unit in which the strand is not engaged thereby to a position in which the strand is snagged

thereby, means for urging the snagger toward the first-mentioned position thereof, an actuator selectively operable for moving the snagger against the snagger-urging means to the position of the snagger in which the snagger snags the strand, and a cutter over which the strand is moved by the snagger for severing the strand.

17. A takeup apparatus, which comprises a rotatable reeling element, a second rotatable reeling element, means mounting the reeling elements in transversely aligned positions for rotating the reeling elements in inrunning directions, an arm carried continuously with and mounted pivotally at the end of the first-mentioned reeling element, a snagger carried by the arm and extending substantially parallel to axis of rotation of the first-mentioned reeling element and radially outside that reeling element so that the snagger is projected over that reeling element when the arm is pivoted toward that reeling element, said snagger being revolved in a predetermined circular path beyond the radial limits of the first-mentioned reeling element, a distributor adjustable transversely to the axes of rotation of the reeling element for distributing a strand upon the second-mentioned reeling element and for guiding the strand to the second-mentioned reeling element in a plane chordally intersecting the path of the snagger, means for urging the snagger to a retracted position beyond the near end of the first-mentioned reeling element as the snagger is moved past the portion of the strand entering the portion of the plane chordally intersecting the path of the snagger so that the snagger clears that portion of the strand, means selectively operable for moving the snagger to a snagging position extending over the near end of the first-mentioned reeling element after the snagger has been moved past the portion of the strand entering said portion of said plane and before the snagger has been moved to the portion of the strand leaving said portion of said plane and for holding the snagger in its snagging position as the snagger is moved to and past the point at which the strand leaves said portion of the plane so that the snagger catches and grips the strand as the strand is moved past the near end of the first-mentioned reeling element, and a cutter positioned outside the circular path of the snagger and in the path in which the portion of the strand between the snagger and the second-mentioned reeling element is moved by the snagger for severing the strand.

18. A takeup apparatus, which comprises a rotatable reeling element, a second rotatable reeling element, means mounting the reeling elements in transversely aligned positions for rotating the reeling elements in inrunning directions, a snagger carried continuously with the first-mentioned reeling element at an end thereof and extending substantially parallel to the axis of rotation of the first-mentioned reeling element and radially outside that reeling element, the snagger being projectable over the first-mentioned reeling element and being revolved in a predetermined circular path beyond the radial limits of the first-mentioned reeling element, a distributor movable transversely to the axis of rotation of the reeling element for distributing a strand upon the second-mentioned reeling element and for guiding the strand to the second-mentioned reeling element in a plane chordally cutting the path of the snagger, means for preventing snagging action of the snagger as the

snagger is moved past the portion of the strand entering the portion of the plane chordally intersecting the path of the snagger, cam means selectively operable for actuating the snagger after it has been moved past the portion of the strand entering said portion of said plane and before the snagger has been moved to the portion of the strand leaving said portion of said plane and for holding the snagger in the position extending over the near end of the first-mentioned reeling element as the snagger is moved to and past the point at which the strand leaves said portion of the plane so that the snagger catches and grips the strand as the strand is moved past the near end of the first-mentioned reeling element, and a cutter positioned outside the circular path of the snagger in the path in which the portion of the strand between the snagger and the second-mentioned reeling element is moved by the snagger for severing the strand.

19. A strand takeup apparatus, which comprises a reel, means for rotating the reel, means connected to one end of the reel and rotated continuously with the reel, an L-shaped snagger provided with a strand-catching notch formed in one arm thereof and having one end of the other arm thereof pivotally connected to the last-mentioned means in a position in which the snagger lies in a plane chordal with respect to the reel and movable between a snagging position in which the first-mentioned arm projects over the portion of the reel most adjacent thereto and a retracted position in which the first-mentioned arm does not extend over that portion of the reel, means normally urging the snagger to its retracted position, cam means carried by the snagger, a manually operable pusher having cam means positioned adjacent to a predetermined portion of the path of the first-mentioned cam means and cooperable with the first-mentioned cam means for pressing the snagger to its snagging position, means for guiding a strand adjacent to the snagger, and means for severing a strand snagged by the snagger.

20. A strand takeup apparatus, which comprises a reel, means for rotating the reel, a disc connected to one end of the reel and rotated continuously with the reel, a snagger provided with a strand catching notch mounted on the disc, carried continuously therewith, and movable between a snagging position in which the snagger projects over the portion of the reel most adjacent thereto and a retracted position in which the snagger does not extend over that portion of the reel, means normally urging the snagger to its retracted position, cam means carried by the snagger, a manually operable pusher having cam means positioned adjacent to a predetermined portion of the path of the first-mentioned cam means and cooperable with the first-mentioned cam means for pressing the snagger to its snagging position, means for guiding a strand adjacent to the snagger, and means for severing a strand snagged by the snagger.
